Application August 17, 1938, Serial No. 225,267
 Renewed January 22, 1940

12 Claims.

(Cl. 40—84)

This invention relates to display signs and particularly to an improved automatically actuated mechanism for successively bringing to view different signs, an object being to provide a simple construction which will secure the results without requiring the attention of an attendant.

A further object of the invention is to provide a mechanism for bringing to view successive sign sheets through a means which moves the sheets to view in opposite directions and which continually functions automatically as long as the power is turned on.

An additional object of the invention is to provide an automatic display machine for bringing the sign sheets to view in succession, wherein means are so formed that the driving means operates continuously and yet there is a dwell after each sign has been moved to a display position.

Another object is to provide a construction wherein the sign sheets may be readily brought to view without danger of tearing the sheets so that as the machine operates the same may repeat and present the sign sheets in good condition.

A further and more detail object of the invention is to provide mechanism for presenting to view different sign sheets in succession and to provide a balanced structure for the mechanism whereby there will be no appreciable momentum of the sheets as the device functions.

In the accompanying drawings—

Fig. 1 is a front view of a display machine disclosing an embodiment of the invention;

Fig. 2 is a vertical sectional view through the machine shown in Fig. 1, the same being taken on an enlarged scale and through Fig. 3 approximately on the line 2—2;

Fig. 3 is a sectional view through Fig. 2 approximately on the line 3—3;

Fig. 4 is a sectional view through Fig. 3 approximately on the line 4—4;

Fig. 5 is an enlarged fragmentary sectional view through one of the spool ends, spool shafts and associated parts;

Fig. 6 is a sectional view through Fig. 5 approximately on the line 6—6;

Fig. 7 is a fragmentary view similar to part of Fig. 5 and illustrating how the parts are positioned immediately before the sign-carrying spool is moved;

Fig. 8 is a side elevation of a roller-carrying bar embodying certain features of the invention;

Fig. 9 is a view similar to Fig. 8 showing the bar at the opposite end of the spool;

Fig. 10 is a side view of a roller, sign sheet and roller rod embodying certain features of the invention;

Fig. 11 is a wiring diagram illustrating the electric circuit and means immediately associated therewith;

Fig. 12 is a fragmentary view of a modified form of spool end to that shown in Fig. 5;

Fig. 13 is an enlarged sectional view through Fig. 12 approximately on the line 13—13;

Fig. 14 is a view partly in section illustrating a modified form of means for producing a dwell after each sign sheet has been moved.

Referring to the accompanying drawings by numerals, 1 indicates a casing provided with a window opening 2 which is preferably closed by a transparent member 3 which is usually of glass. The casing 1 may be made of wood, metal, or other material, and arranged so that the front, rear, top, bottom and sides are firmly held together, the front and rear being removably secured in place. The casing is adapted to be supported on a wall or other support at any desired point so that the successive sheets 4 and 5 may be brought to view for displaying the matter thereon. These sign sheets are adapted to be moved in opposite directions and simultaneously so that when the sign sheet 4 moves upwardly it gradually disappears and the sign sheet 5 gradually appears. On the next motion of the sign sheets a new sheet will move downwardly and take the place of sheet 4 while the old sheet 5 will move downwardly and out of sight. As the front and rear are removable the signs may be removed or changed either from the front or rear as desired.

In providing a mechanism to accomplish these results and to present a structure which will function automatically and continuously for either long or short periods of time, improved mechanism has been provided as illustrated particularly in Figs. 2 to 11 inclusive.

The device is adapted to be actuated by power from electric motors but, if desired, it could be operated by power from other sources. As shown in Fig. 3, there are provided electric motors 6 and 7 which are connected to a suitable source of current which may be turned on and off manually as desired. These motors are arranged in position to operate in opposite directions as indicated by the arrows in Fig. 2. The rotor of motor 6 is connected to a shaft 8 while the rotor of motor 7 is connected to a shaft 9. These two shafts are

connected to a suitable reducing gear 10 adapted to rotate a pinion 11 in one direction when one motor is functioning and in the opposite direction when the other motor is functioning. It will be understood that the motors function at different times. The reducing gear may be of any desired kind but may be such that when the motor 7 is functioning to drive the parts the rotor of motor 6 will be rotated idly in a reverse direction, and when the motor 6 is functioning the reverse action takes place. As illustrated in Fig. 11 and as hereinafter fully described, means is provided for reversing the direction of rotation of the pinion 11 as soon as a sign sheet has been brought fully to view.

As shown in Fig. 3, the pinion 11 continually meshes with a gear wheel 12 pinned or otherwise rigidly secured to a drive shaft 13. This shaft rotates part of the time in one direction and then immediately reverses and rotates in the opposite direction without any dwell as long as the machine is functioning. Sprocket wheels 14 and 15 are connected to shaft 13 at the respective ends and over these sprocket wheels operate the respective chains 16 and 17. Each of these chains is provided with a lowering hook or abutment 18 and a raising hook or abutment 19. The parts are so apportioned that the hooks 18 will move intermittently to a position slightly below the lower edge of opening 2 and then the hooks 19 will move upwardly to a position slightly above the upper edge of opening 2. This back-and-forth motion of these hooks and of the chains which carry the same continues as long as the device is operating. The hooks 18, as heretofore fully described, will act on one of the upper sign sheets to move the same downwardly, while the hooks 19 will operate on one of the lower sign sheets to move the same upwardly.

As illustrated in Fig. 4, there is provided a construction which may be termed a spool 20 at the upper part of the casing 1 and a second spool 21 at the lower part of the casing. These spools are identical but operate in opposite directions. It is therefore thought that a description of one will be sufficient to serve them both. For instance, spool 20 is provided with spool ends or disks 22 and 23. Each of these disks is provided with radiating apertures 24. As illustrated in the drawings, there have been provided twelve of these radiating apertures or slots but it is evident that a greater number or even a less number might be used without departing from the spirit of the invention. On one of the disks 22 there are provided a number of roller-carrying bars 25 and on the other a number of roller-carrying bars 26. These bars are constructed as shown in Figs. 8 and 9. Bar 25 is provided with apertures 27 for receiving ball-retaining members 29 and 30, as shown in Fig. 6, and a third aperture 31 for receiving the small end of a rod 32. The opposite end of rod 32 is provided with squared portions 33 which fit into a notch 34 in the bar 26. Bar 26 is provided with apertures 35 for receiving spring-pressed balls, as shown in Fig. 6. It will be noted that the disk 22 is provided with an auxiliary disk 36 which may be welded or otherwise secured in place and which is provided with sockets for accommodating the respective springs 37 and 38 which hold the balls 30 in functioning position. It will be understood that there is provided a pin 32 for each of the notches or slots 24 and each pin is connected with what may be termed a sign roller 39. This roller is provided with a coil spring 40 so that the roller,

spring and associated parts will have a tendency to rotate in one direction, the structure being substantially the same as an ordinary shade roller without the locking pawl. A sign sheet is secured to and wound on each of the rollers 39. Each of these sign sheets carries a rod 41 at the outer free end. This rod normally rests in the notch 42 of bar 25 at one end of the spool and rests in a notch 42' at the other end of the spool. As illustrated in Figs. 4 and 6, each of the sign sheets is provided with a pair of cutouts 43 for receiving certain actuating members herein fully described and which engage the rod 41 in these cutouts so as to raise or lower the sign sheets as the device functions.

As illustrated in Fig. 2, there is a sign sheet for each roller 39 and there is provided a roller for each of the slots 34. The rods 41 rest in the notches 42 and 42' of the respective bars 25 and 26 of the spool 20 until positively moved therefrom by raising and lowering members 44. As shown in the drawings there have been provided two members 44 but a greater number may be used without departing from the spirit of the invention. These members are rigidly secured to the slide bar 45 by welding or other means. Each of these members is provided with an upper hook 46 and a lower hook 47 for engaging the respective rods 41 as hereinafter fully described. The slide bar 45 has an upstanding plate or bar 48 adjacent each end and these plates carry a bar 49 which is parallel to the bar 45. The bar 45 is provided with a number of apertures 50 which may be rectangular or some other shape and which coact with apertures 51 in a slide bar 52 slidingly mounted in bar 45. The slide bar 52 has an extension at one end which carries a friction roller 53, which roller rolls over the undulating surface 54 of the casing 1. A contactual spring 55 (Fig. 4) is connected to the extending end 56 of the slide bar 52 and at 57 to the bar 45 so as to give the slide 52 a tendency to move to the right as shown in Fig. 4. As the bar moves upwardly and downwardly the friction roller 53 will cause the slide 52 to move back and forth in conjunction with the action of the spring 55.

As there are provided a number of electric lamps 58 (Fig. 2) in the casing 1 and in front of the reflector 59, light will be projected through the openings 50 and 51 but a blinking action will be produced. This is designed to call attention to the sign as moving lights usually secure this result. This blinking action will take place as the bar 48 moves upwardly and downwardly. It will be noted from Figs. 2 and 3 that the plates or bars 48 are each provided with an aperture and through these apertures the respective guide bars or standards 60 and 61 slide. Tubular extensions or sleeves 62 and 63 extend upwardly and downwardly on the respective bars 48 so that the bar or frame 45 may easily slide upwardly and downwardly during the functioning of the device. It will be noted that the bars or plates 48 are each provided with an extension 64 adapted to be engaged by the respective hooks 18 and 19 and an extension 65 adapted to engage and move a lever 66 illustrated particularly in Figs. 5 and 6. The sleeve 63 is provided with an insulated extension 67 adapted to engage and close the switch 68 when the parts are in the lowest position, while the sleeve 62 is provided with an insulated extension 69 adapted to engage and close the upper switch 70 when the parts are in their highest position. When the switch 70 is

closed current is switched off from one of the motors and on to the other so that the mechanism will immediately begin to function to move the hook 18 downwardly, while the reverse is true in regard to the actuation of switch 68, namely, when switch 68 functions hook 19 will begin to move upwardly and continue to move upwardly until the extension 69 actuates switch 70. These switches are only momentarily closed when the circuits of the respective motors are closed for the desired length of time to secure the proper movement of the parts to cause the various hooks to function as just described.

In order to balance the chains and associated parts there is provided a weight 71 and a suitable guide 72 on each side of the device. Cables 73 extend upwardly from these weights and have pulleys 74 and 75 adjacent each end of the spool so that the end of the cable opposite the weights will be connected to the frame or bar 45 at the respective points 76 and 77 (Fig. 4). This arrangement provides a desired counterbalance so that when either motor stops the chain will stop and also the sign sheet which has just been moved.

When the parts are functioning to move a sign sheet, as for instance sheet 4, downwardly as shown in Figs. 1 and 5, the respective hooks 46 will be in engagement with the rod 41 of one of the sign sheets carried by the spool 20 while the hook 47 will be engaging the rod 41 carried by the spool 21. As illustrated in Fig. 5, the frame or bar 45 is moved downwardly under the action of hook 18. The parts will then move from the position shown in Fig. 5 to that shown in Fig. 7 wherein the rod 41 carried by hook 47 will come to rest in the notch 42' of one of the bars 26. This bar at this time is stationary and, consequently, as the member 44 continues to move downwardly hook 47 will move below the bar 26 which has just received the rod 41. As the parts continue to move downwardly the upper sign sheet 4 will continue to move downwardly and the extension 65 of bar 48 will strike the end of lever 66, as shown in Fig. 7, and move this lever downwardly to the dotted position shown in Fig. 5. This lever is journaled on the shaft 21' of spool 20 and as the lever is moved downwardly the rear extension 78 will move upwardly. A pawl 79 is pivotally mounted at 80 to the extension 78. This pawl will engage in one of the teeth 81 of a ratchet wheel 82 and move the shaft 21', the spool end 22 and associated parts, as well as the spool end 23. It will be understood that the respective spool ends are pinned or otherwise secured to shaft 21' so that both ends will move at the same time and in the same direction. A flat spring 83 is secured to the casing 1, as shown in Fig. 2, and pressed against the ratchet wheel 82 so as to prevent any momentum thereof.

When the member 44 with its hook 46 moves to the dotted position shown in Fig. 5, it has reached its lowermost position and, as illustrated in dotted lines in Fig. 2, the insulated extension 67 will strike the switch 68 for causing a reversal of the driving means. As the pawl 79 moves the ratchet wheel 82 the upper rod 41, which has been left in the socket 42 as shown in Fig. 7, will move downwardly so that upon the return movement of hook 47 said hook cannot again engage this particular rod but will engage rod 41 of the next sign sheet, and as the hook and associated parts move upwardly the next sign sheet will be brought to view opposite the opening 2. As the next sign sheet is being moved upwardly as just

described the bar 41 carried by the hook 46 will be moved upwardly under the action of the spring on the pawl carrying this particular sign sheet. It will be seen, therefore, that by reason of the coil springs 40 whenever a sign sheet is released by an upward or downward movement of member 44, the coil spring 40 associated therewith will rewind the sign sheet so that it will be ready for the next unwinding. As the hooks 18 and 19 move downwardly a sign sheet from the upper spool will be moved downwardly and then a sign sheet from the lower spool will be moved upwardly and the first sign sheet will be rewound and the upper spool turned one notch so as to bring the second upper sign sheet into place. This action is continued until all twelve of the upper and all twelve of the lower sign sheets have been brought to view. If there should be more than twelve sign sheets they will all be brought to view before the sign sheets will repeat.

As illustrated in Fig. 2 when the hook 18 moves downwardly to the lower end of the opening 2 the frame or bar 45 will remain in its lower position while the hooks 18 and 19 will move. Hook 18 will move upwardly and leave the vicinity of bar 45 while hook 19 will slowly move toward the bar 45 and when it reaches the same it will interlock with the extension 49 and move the frame or bar 45 upwardly and all the parts associated therewith. During the time the hook 19 is in a certain sense catching up with the frame or bar 45, there is a dwell or stationary period for the upper sign sheet. When the hook 19 moves to its highest position and then starts back there will be a similar dwell or stationary period for the lower sign sheet which is exposed through the opening 2. As there are no complicated parts present the mechanism will continue to function continuously for the period of time desired but it will be evident that the exposure of the respective sign sheets on the respective spools of the mechanism will repeat the exposures. This repetition is continued as long as the machine functions. At any time an operator may turn off the current and remove the old sign sheets and substitute new ones.

Referring more particularly to Fig. 11, it will be seen that there are provided a pair of supply lead-in wires 84 and 85, the lead-in wire 85 being divided and connected with one end of the respective magnets 86 and 87. The end 88 of magnet 87 is connected through wire 89 to contact member 90 of switch 70 while the end 91 of magnet 86 is connected through wire 92 to contact member 93. The respective contact members 94 and 95 of the respective switches are connected by wires 96 and 97 to the lead-in wire 84. This lead-in wire is connected by wire 98 to one side of the respective members 6 and 7 and at the other side through wires 99 and 100 to the contacts 101 and 102. An armature 103 is connected at 104 to wire 85 and is pivotally mounted so that when magnet 86 is energized it will engage contact 101, but when magnet 87 is energized it will engage contact 102. By reason of this construction when the switch 68 is closed temporarily magnet 98 will be magnetized temporarily and will swing armature 103 to the position shown in Fig. 11 where it remains until the switch 70 is temporarily closed. The temporary closing of switch 70 will temporarily energize magnet 87 and swing the armature 103 away from contact 101 and into engagement with contact 102, thus switching out of the circuit motor 6 and switching into the circuit motor 7. This will cause a re-

versal of the movement of the pinion 11 and associated parts as heretofore described.

As a modified construction to that shown in Fig. 5, the spool end 22 and, in fact, all of the spool ends may be provided with hook extensions 105 which will do away with the construction shown in Figs. 8 and 9. However, there is provided a spring 106 for each of the rollers 39 so as to receive the squared end 107 as shown in Fig. 13. This rectangular or squared end fits into a rectangular or squared opening 108 in the spring so as to prevent the rotation of the rod 32. One end of the spring 40 is connected with this rod and the other end with the roller 30 so that when the respective pins 41 are released the sign sheets will quickly be wound on their respective rollers, as shown in Fig. 10, but may be readily pulled therefrom by the actuating member 44.

In Fig. 14 a slightly modified form of construction for producing a dwell in the movement of the frame or bar 45 is shown. In this form of the invention the respective sprocket wheels 14 and 15 are provided with a shaft 109 which has a threaded section 110 on which a traveling sleeve 111 is mounted. This sleeve has gear teeth 112 on the exterior surface continually meshing with the pinion 11. A clutch member 113 is pinned or otherwise rigidly secured to the shaft 109 near one end and a similar clutch member 114 is pinned or otherwise rigidly secured to shaft 109 adjacent the other end. The interiorly threaded and exteriorly geared sleeve 111 is provided with coating clutch members 113' and 114'. If the pinion 11 should be rotated in a certain direction the sleeve 111 would move downwardly, as shown in Fig. 1, but the sprocket wheels 14 and 15 would not function until the clutch member 114' engages clutch member 114. This will produce a dwell in the movement of the chain 40 and, consequently, a dwell in the movement of the bar 45 and associated parts.

In the preferred form of the invention, as shown in Figs. 2 and 3, the chain is continuously moving either in one direction or the other and the dwell is caused by the spacing of the hooks 18 and 19. In the construction shown in Fig. 14 the dwell is caused by the fact that the sprocket wheels are stationary as the sleeve 111 moves from one clutch member to the other.

650. I claim:

1. A display exhibitor including a casing having a window, a group of sign sheets positioned in said casing out of alignment with said window, a second group of sign sheets positioned in said casing out of alignment with said window and on the opposite side to the first-mentioned group, an independent rotatable roller for each sign sheet for both of said groups, a spring for each of said rollers for giving the rollers a tendency to rotate and wind said sign sheets thereon, a reciprocating chain, sign sheet shifting means actuated by said chain for successively engaging and moving the sign sheets of the respective groups for unwinding the same and also for bringing them to a position in line with said window, said means functioning to unwind one sign sheet of one group while releasing one sign sheet of the other group, and means spaced apart along said chain so that they will function at spaced intervals while the chain continues to function, said last-mentioned means causing the first-mentioned means to function at spaced intervals, whereby there will be a dwell in the movement of said sign sheets, said last-mentioned means being located on the chain so that said dwell will occur as any sign

sheet completes its movement into a position in front of said window.

2. A display exhibitor, as set forth in claim 1, characterized by oppositely facing hooks secured to said chain for engaging and moving said sign sheet shifting means at spaced intervals in opposite directions.

3. A display exhibitor including two groups of sign sheets, a pair of reciprocating chains, means including sign sheet shifting means for successively engaging and moving the sign sheets of the respective groups to a display position, and means actuated by said chains functioning to move one sign sheet of one group to said display position while releasing one sign sheet of the other group, said last-mentioned means being spaced apart whereby as said chains reciprocate the last-mentioned means will be brought into functioning engagement with the first-mentioned means at spaced intervals so that a dwell between the successive movements of said sheets will be produced of a duration corresponding to the spacing of the second-mentioned means and the speed of said chains.

4. A display exhibitor, as set forth in claim 3, characterized by the use of oppositely facing hooks secured to said chains at spaced intervals as the means for actuating said sign sheet shifting means.

5. A display exhibitor including a casing having a window, a group of sign sheets positioned in said casing out of alignment with said window, a second group of sign sheets on the opposite side of said window positioned out of alignment with said window, a sign sheet shifting structure formed with means for simultaneously engaging the end portion of one sign sheet of each of said groups, means engaging said sign sheet shifting structure for causing the same to move the sign sheet of one group to a position opposite said window while releasing the sign sheet of the other group, a reciprocating member, a pair of spaced abutments secured to said reciprocating member positioned to cause said sign sheet shifting structure to move to one extreme position, dwell and then move to the other extreme position and dwell, and means for causing said reciprocating member to function.

6. In a display exhibitor, a spool having end disks, each disk being formed with a plurality of radiating slots, a roller carrying bar for each of said slots, means for securing said bars to said disks, each of said bars having a notch, a sign sheet carrying roller for each of said slots, a rod for each of said rollers, said rollers being rotatably mounted on said rods, one end of each of said rods being flattened with the flattened part extending through a notch in one of said bars, a coil spring for each of said rollers mounted to surround the rod extending through the roller with one end rigidly secured to the rod and the other end secured to the roller, a sign sheet for each of said rollers secured at one end to the roller and normally wound on the roller, each of said bars having a notch at the outer end, a rod secured to the free end of each of said sign sheets normally resting in the notch in the bar with which it is associated, reciprocating means on its outward stroke engaging and moving the rod on one of said sign sheets for displaying the sign sheet associated with the rod and on its return stroke releasing the rod so that the coil spring associated therewith will rewind the sign sheet on the roller, and means actuated by said

reciprocating means for rotating said spool sufficiently upon the completion of its return reciprocation to cause the rod of the next adjacent sign sheet on said spool to be in line to be engaged and moved to a display position.

7. In a display exhibitor, a spool having end disks, each disk having means presenting a radially protruding hook structure, a plurality of normally wound sign sheets mounted on said spool, means for rewinding each sign sheet when released, each of said sign sheets having at its outer end a rod, said rods normally resting on said hook structure, a reciprocating member for successively engaging said rods and unwinding said sign sheets to expose to view the sign sheets, a pawl and ratchet wheel secured to said spool to rotate the same, and a normally spring-held pivotally mounted lever for causing said pawl to intermittently rotate said spool, said lever having one end extending into the path of movement of said reciprocating member so that said lever will be swung for causing said pawl to function each time said reciprocating member moves to one end of its travel.

8. A display exhibitor having a casing with a window, a rotatable spool in the casing adjacent each end, a plurality of coiled sign sheets carried by each of said spools, means for recoiling said sign sheets, a pair of spaced reciprocating chains, a pair of spaced abutments carried by each of said chains, a pair of reversible electric motors for causing said chains to reciprocate, a frame formed with a pair of spaced abutments adapted to continuously interlock with the free end of one of the sign sheets of each spool, the abutment on each chain being positioned to engage said frame for causing the same to reciprocate and move one sign sheet to a position to be viewed through said window and at the same time to gradually release the other sign sheet, said frame having a dwell at each end of its travel by reason of the spacing of the abutments on said chains, and means coacting with the first-mentioned abutment and said spool for exchanging the free end of a new sign sheet for an old sign sheet at each end of the travel of said frame.

9. A display exhibitor comprising a casing having a window, a spool at each end of said casing, a plurality of normally coiled sign sheets carried by each of said spools, means for recoiling said sign sheets after each uncoiling, and means for alternately uncoiling a sign sheet from said spools and moving the same to be exposed through said window, said means including a sprocket wheel adjacent each end of said casing, a sprocket chain mounted on said sprocket wheel, a pair of electrically actuated reversely rotatable motors for driving said sprocket chain, means for transmitting motion from said motors to one of said sprocket wheels, a vertically movable frame having means for alternately engaging the free end of a sign sheet on the upper spool and then a sign sheet on the free end of the lower spool, spaced abutments carried by said chain for moving said frame to its highest point and then to its lowest point of travel, the spacing of said abutments and the speed of said chain determining the dwell of the frame at the end of each of its travels, an electric circuit for each of said

motors, a switch for closing said circuit alternately, and means actuated by said frame for causing said switch to function at each end of the travel of said frame.

10. In a display exhibitor, a plurality of groups of sign sheets, means for alternately moving a sign sheet from said groups to a display position, and means for producing a dwell at the end of the movement of each sign sheet, said means including a pair of sprocket wheels, a shaft connecting said sprocket wheels, said shaft intermediate its ends having a threaded section, an internally threaded sleeve positioned to travel on said threaded section, said sleeve having on its exterior surface gear teeth extending the full length of the sleeve, a reversible gear wheel meshing with said sleeve whereby when said gear wheel is rotating in one direction said sleeve will move toward one sprocket wheel and when it is rotated in the opposite direction said sleeve will move toward the other sprocket wheel, and a clutch member secured to said shaft substantially at each end of said threaded section whereby when said sleeve engages either of said clutch members said shaft will rotate in the same direction as said sleeve.

11. In a display exhibitor, a casing having a window, a group of sign sheets on each side of said window, means for alternately bringing a sign sheet from one group to a position in line with said window and then a sign sheet from the other group, said means including a frame movable back and forth across said window having a number of openings therein, a shutter carried by said frame for said openings, means carried by said frame and said casing for actuating said shutter whereby said openings will be opened and closed as the frame moves, and illuminating means arranged in said casing for illuminating said sign sheets as they come opposite said window, light from said illuminating means shining through said openings when said shutter is in an open position and by reason of the actuation of said shutter there will be a blinking action produced.

12. In a display exhibitor, a casing having a window, a group of sign sheets above said window, a group of sign sheets below said window, means including a frame movable upwardly and downwardly across said window for alternately bringing a sign sheet from the upper group to a position in line with the window and then a sign sheet from the lower group, mechanism for actuating said means, said mechanism including a pair of motors functioning in opposite directions, a circuit for each of said motors, a switch for closing said circuits alternately, said switch including a switch arm formed as an armature, an electromagnet on each side of said arm, and a separate circuit for each of said electromagnets, each of said separate circuits having a normally open switch, and means carried by said frame for alternately temporarily closing said separate switches, said means functioning as said frame reaches the extreme end of its travel in either direction whereby one of said motors will function to raise said frame and the other motor will function to lower said frame.

JOB HUTCHINSON.
